(57) **CLAIM**

The ornamental design for a firearm suppressor as shown and described.

DESCRIPTION

FIG. 1 is a perspective of a firearm suppressor;
FIG. 2 is a front view of the firearm suppressor;
FIG. 3 is a right end view of the firearm suppressor;
FIG. 4 is a top plan view of the firearm suppressor;
FIG. 5 is a rear view of the firearm suppressor;
FIG. 6 is a left end view of the firearm suppressor; and,
FIG. 7 is a bottom plan view of the firearm suppressor.

The evenly broken lines disclose unclaimed portions of the firearm suppressor; the dash-dot broken lines disclose unclaimed boundaries of the claim. The broken lines form no part of the claimed design. Drawings disclose indeterminate length through the use of dash-dot break-away lines. The appearance of any portion of the firearm suppressor between the break-away lines form no part of the claimed design.
